CLAIM

The ornamental design for a fiber optic splitter module with surface ornamentation, as shown and described.

DESCRIPTION

FIG. 1 is a front, bottom and left side perspective view of a fiber optic splitter module with surface ornamentation illustrating our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is a front, bottom and left side perspective view thereof, in an alternate condition.

The broken lines in the drawings are included for the purpose of illustrating environmental structure and form no part of the claimed design. The long dash-short dash lines represent the boundaries of the claimed design. In FIGS. 1, 2, and 8, the shading indicates a contrast in color, where the darker shading may have a different color than the lighter shading or the same color as the lighter shading, and the unshaded area may have no color or a different color than the darker shading and the lighter shading.
